(57) **CLAIM**

The ornamental design for a wheel rim, as shown and described.

DESCRIPTION

4. Wheel rim

4.1 is a perspective view of a wheel rim embodying our new design;

4.2 is a front elevation view thereof;

4.3 is a rear elevation view thereof;

4.4 is a right side elevation view thereof;

4.5 is a left side elevation view thereof;

4.6 is a top plan view thereof; and

4.7 is a bottom plan view thereof.
